(57) **CLAIM**

The ornamental design for a flexible hair clip, as shown and described.

DESCRIPTION

FIG. 1 is a perspective view of a flexible hair clip;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a bottom plan view thereof; and,

FIG. 7 is a top plan view thereof.

FIG. 8 is a perspective view of the present invention in a partially bent configuration;

FIG. 9 is a top plan view thereof.

FIG. 10 is a perspective view of the present invention in the circular configuration with the ends of the flexible wave shaped body clipped together; and,

FIG. 11 is a top plan view thereof.
